[57] CLAIM

The ornamental design for a partition planter, as shown and described.

DESCRIPTION

FIG. 1 is a perspective view of a partition planter showing my new design, the plant and corner of a partition being shown in broken lines for illustrative purposes only;

FIG. 2 is a top plan view thereof;

FIG. 3 is a bottom plan view thereof;

FIG. 4 is a side elevational view of the side opposite that shown in FIG. 1;

FIG. 5 is an end elevational view of the end opposite that shown in FIG. 1.

Fig. 5
